UNITED STATES PATENT OFFICE.

GEORGE C. JENSEN, OF OAKLAND, CALIFORNIA.

AUTOMOBILE LOCK MECHANISM.

1,221,994.

Specification of Letters Patent. Patented Apr. 10, 1917.

Application filed October 31, 1916. Serial No. 128,706.

To all whom it may concern:

Be it known that I, GEORGE C. JENSEN, a citizen of the United States, residing at Oakland, in the county of Alameda and State 5 of California, have invented certain new and useful Improvements in Automobile Lock Mechanism, of which the following is a specification.

The present invention relates to a locking 10 mechanism for movable levers, and is particularly adapted for application to the control levers of a motor vehicle.

The object of the invention is to provide a simple and practical device of the type described, which may be easily installed upon a type of lever used extensively for shifting the variable speed gears of motor vehicles, and as such constitutes an improvement on the device for which I have filed application 20 for United States Letters Patent, under date of September 21, 1916, Serial No. 121381, for lock mechanism for automobiles.

The general advantages to be gained by the use of the present invention are similar 25 to those set forth in said previous application, namely that, by means of the invention, the gear shifting lever of a motor vehicle may be easily and securely locked in its neutral position, to prevent the movement of 30 the vehicle under its own power, without interfering with the movement thereof by hand, as for example, when it is desired to move the vehicle from place to place in a garage.

35 In order to comprehend the invention, reference should be had to the accompanying drawings, wherein:—

Figure 1 is a central longitudinal section of my lock as applied to a well known type 40 of motor vehicle gear-shifting lever.

Fig. 2 is a detailed longitudinal section of the lever fulcrum, showing the locking bolt taken at right angles to Fig. 1.

Figs. 3 and 4 are transverse sections taken 45 in the direction of the arrows on the lines 3—3 and 4—4, respectively, of Fig. 1.

In the drawings, the reference numeral 1 designates a lever of a type commonly used in motor vehicles, having an offset upper 50 portion 2, at the upper end of which is a handle, not shown in the drawings. Said lever 1 is arranged for swinging movement in two vertical planes, and for this purpose is freely fulcrumed upon a horizontal shaft 3, the latter being fixed, as by means of 55 dowels 4, in upwardly extending fixed arms

or brackets 5. The lower end 6 of the lever 1 is shown in Fig. 1 of the drawings as adapted for engagement with the shifter rods of a sliding gear mechanism, said shifter rods and mechanism being well known in the art and therefore not shown in the drawings. The usual spring for holding the lever 1 in its vertical position, laterally, is shown at 7, and an articulated 60 housing for inclosing the fulcrum of said lever is shown at 8.

The lower, or straight portion of the lever 1, is formed with a lineally disposed cylindrical chamber 9, having an open upper end 10 at the offset in said lever. The upper portion 9' of said chamber is enlarged to receive a suitable lock 11, said lock being retained in position by the annular shoulders 12 and 13, at the ends of said enlarged 65 chamber portion 9'.

Any suitable lock may be employed, preferably of the cylinder type, being indicated at 11, in Fig. 1 of the drawings. The projecting lower end 14 of the cylinder of said lock is securely fixed to the upper end of a cylindrical sleeve 15, rotatably carried within the chamber 9. Within said sleeve 15 is a lineally slideable head 16, having a lug or pin 17, extending laterally therefrom, and projecting through aligned lineally disposed slots 18 and 19, Fig. 4, in the sleeve 15 and the lever 1 respectively. A knob 20 is secured upon the outer end of said pin 17, by means of which said pin and the head 16, 90 may be moved lineally within the sleeve 15.

Mounted for transverse sliding movement within the head 16, is a latch member 21, Figs. 1 and 3 of the drawings. Said latch has an inclined outer end portion 22, adapted 95 to project through an aperture 23 in the sleeve 15, and into a notch 24 in the lever 1. A spring 25 is provided behind said latch 21 to force the same outwardly to lock said head 16 against lineal movement.

Secured to the head 16 is a lineally disposed downwardly extending rod 26, Figs. 1 and 2 of the drawings, said rod passing through a suitable bore or channel 27 in the lever 1, and carrying a bolt 28, adapted to 100 enter a socket 29 in the transverse fulcrum shaft 3, to securely lock the lever 1 against any movement with respect to said shaft. A spring 30, Fig. 1, positioned below the head 16, acts to normally retain said head and the bolt 28 in their upper, or unlocked, positions.

To operate the device to lock the lever 1,

it is only necessary to depress the head 16 by means of the projecting knob 20, to move the bolt 28 into the socket 29. This may be easily done, in the device illustrated, by a 5 movement of the operator's foot. This depression of the head 16 allows the latch 21 to project into its socket 24, thereby retaining said head and the bolt 28 in their lower or locking positions. It is understood, of course, that the lever 1 must be in the proper position, before the same can be locked.

When it is desired to unlock the lever, the lock cylinder 14 is turned, by means of a suitable removable key 31. This rotates the 15 sleeve 15, and by so doing forces the latch 21 inwardly, the edge of the aperture 23 in said sleeve riding upon the inclined surface 22 of said latch, as will readily be seen from Fig. 3 of the drawings. As soon as the latch 20 21 is entirely within the head 16, said head is raised by the spring 30, and the bolt 28 is thereby withdrawn from its socket 29. If, for any reason, said bolt should stick, so that the spring 30 could not withdraw it, the 25 head 16 can be forcibly lifted by means of the projecting knob 20.

The sleeve 15, of course, must be in the proper position to allow the latch 21 to pass through the aperture 23 thereof, to enter the 30 socket 24. This position of said sleeve is secured by turning the lock cylinder 14, by means of its key 31, in a counter-clockwise direction until the rear edge of said aperture 23 abuts against the straight back of the 35 latch 21. It will readily be understood that, if the lock cylinder be normally left in this position, that is to provide alinement between the aperture 23 in the sleeve 15 and the socket 24, the bolt 28 can be operated to 40 lock the lever without necessitating the use of the key. Said key of course, must be used to unlock the device.

In the preferred form of the device here- 45 with illustrated, the fulcrum pin 3 of the lever 1 is fixed by means of the dowels 4, and said lever is permitted to oscillate about said pin, as well as to rock laterally there- 50 upon. It is obvious however, that the pin 3 may be arranged to oscillate with the lever 1, turning in its supports 5. In this case the bolt 28, would lock the lever only against lateral rocking movement upon the pin 3.

Other changes of like nature may be made 55 in the form and construction of the device as herewith illustrated and herein described, without in any way affecting the essential principles of the invention. Moreover, the invention is not restricted to use upon motor vehicle gear-shifting levers, but may be em- 60 ployed in connection with any lever of suitable form and construction. It is therefore my wish to be understood as claiming the invention as broadly as the state of the art will permit.

Having thus described the invention,

what I claim as new and desire to be protected by Letters Patent is:

1. In combination with a movable lever and an associated stationary member; a lineally movable member, within said lever, adapted to engage said stationary member for locking the lever thereto; a latch member carried by said lineally movable member for automatically retaining the same in locking position by engagement with said lever and rotatably mounted lock controlled means capable of movement relative to said latch for releasing the same. 70

2. In combination with a movable lever and an associated stationary member; a lineally movable member, within said lever, adapted to engage said stationary member for locking the lever thereto; a transversely movable latch member carried by said lineally movable member and provided with a beveled face for automatically retaining the same in locking position; and lock controlled means capable of movement to engage said face for engaging and releasing said latch member. 85 90

3. In combination with a fulcrum member and a lever carried thereby and adapted for movement relative thereto; a lineally movable member associated with said lever and adapted to engage said fulcrum member to lock said lever thereto; a latch member carried by said lineally movable member for retaining the same in locking position, and rotatable lock controlled means for releasing said latch member. 95 100

4. In combination with a fulcrum member having a socket, a lever carried by said fulcrum member and adapted for movement relative thereto; a lineally movable bolt associated with said lever and adapted to enter said socket to lock said lever to said fulcrum member; a transversely movable latch member carried by said bolt for retaining the same in locking position; an axially rotatable lock controlled means carried by said lever for releasing said latch member. 105 110

5. In combination with a fulcrum member, and a lever carried thereby and adapted for movement relative thereto; a lineally movable member associated with said lever and adapted to engage said fulcrum member to lock said lever thereto; a latch member carried by said lineally movable member for retaining the same in locking position; and rotatable lock controlled means surrounding said lineally movable member and through which said latch extends for releasing said latch member. 115 120

6. In combination with a fulcrum member and a lever carried thereby and adapted for movement relative thereto; a lineally movable bolt, within said lever, adapted to engage said fulcrum member to lock said lever thereto; a head carried by the upper 125 130

end of said bolt; a latch member mounted in said head and adapted to engage the lever to hold said bolt in locking position; a movable sleeve surrounding said head with-
5 in said lever for controlling said latch member; and lock controlled means for actuating said sleeve.

7. In combination with a fulcrum member, and a lever carried thereby, and adapted for movement relative thereto; a lineally movable bolt, within said lever, adapted to engage said fulcrum member to lock said lever thereto; a head carried by the upper end of said bolt; a transversely movable

latch member mounted in said head and 15 adapted to engage the lever to hold said bolt in locking position; a rotatable sleeve surrounding said head within said lever for controlling said latch member; a lock controlled means for actuating said sleeve. 20

In testimony whereof I have signed my name to this specification in the presence of two subscribing witnesses.

GEORGE C. JENSEN.
